UNITED STATES PATENT OFFICE.

WALTER S. BARKER, OF CAMBRIDGE, MASSACHUSETTS.

STORM-COAT.

984,180.

Specification of Letters Patent. Patented Feb. 14, 1911.

Application filed November 15, 1909. Serial No. 528,008.

To all whom it may concern:

Be it known that I, WALTER S. BARKER, of Cambridge, in the county of Middlesex, State of Massachusetts, have invented an Improvement in Storm-Coats, of which the following is a specification.

Storm coats of ordinary construction having two overlapping front portions provided with fasteners, for attaching them together, 10 do not protect the wearer against a driving storm, which finds its way to the wearer between the overlapping front portions.

The employment of a storm-shield in the form of an additional overlapping portion 15 attached to one of the front portions, and adapted to extend over the other front portion results in the production of a tortuous passage, and assists in preventing the storm from driving directly to the wearer between 20 the front portions, but does not entirely exclude the water.

This invention has for its object the interposition of a storm-strip in the tortuous passage, between the overlapping closing portions 25 for the front opening of the coat, which is attached to one of the closing portions remote from the entrance to the passage between said portions, by which water, entering said passage, will, on reaching the 30 storm-strip, be directed downward, and thereby prevented from reaching the wearer, said strip being arranged sufficiently remote from the entrance to substantially check the passage of water, even when said entrance 35 gapes open, as it frequently does. If desired two storm-strips may be arranged in said passage which are attached respectively to two of the closing portions.

Figure 1 is a front elevation of a storm-coat embodying this invention, the outer overlapping closing portion being broken away to expose a storm-strip which is arranged on the front side of the adjacent overlapping closing portion, and said adjacent overlapping closing portion also being broken away to expose another storm-strip which is arranged on the front side of another overlapping closing portion which latter serves as the storm-shield. Fig. 2 is an enlarged sectional detail of a portion of the coat shown in Fig. 1, taken on the dotted line 2—2. Fig. 3 is a similar sectional detail of a modification to be referred to. Figs 4 and 5 are sectional details of other modifications to be referred to.

a and *b* represent, respectively, the two

usual overlapping closing portions for the front opening of a coat, which are adapted to be attached together by suitable fastenings. The closing portion *b*, has arranged 60 on its front side a storm-strip *c*, which, as here shown, is made by turning over the edge of said closing portion *b* upon the front side of said portion *b* for a short distance, and securing it thereto by a line of stitches *c'*, arranged near the line of fold, so that the edge of said overturned portion is free or unattached and is or may be extended forward 65 more or less.

The storm-coat is ordinarily made of oiled 70 cloth, or other waterproof material, which is quite stiff, so that the free or unattached edge of the storm-strip may be inherently held in a forwardly-extended position. Said storm-strip is arranged remote from the entrance 75 to the passage between the overlapping portion, so that, even should the entrance thereto gape open at different places, said strip will still serve to check the passage of water. The storm-strip *c* is preferably, 80 but not necessarily, formed in this manner, as, for instance, it may be made as a rib or wale, see Fig. 4, produced by interposing a cord *f* between the lining and the outer portion, which may be held in place by lines of 85 stitches at opposite sides thereof. More than one rib or wale may be employed if desired.

The coat has three overlapping closing portions, and as shown in Figs. 1 and 2, the 90 inner closing portion *d* is intended to serve as a storm-shield, and it is attached along one edge only to the back side of the outer closing portion *b*, and in such case, if desired, two storm-strips may be employed, 95 one, as *c*, on the front side of the portion *b*, and another, as *c'*, on the front side of the shield *d*; or, as shown in Fig. 3, wherein the outer overlapping portion is intended to serve as a storm-shield, the storm-strip may 100 be arranged on the front side of the inner overlapping portion *b*, and also, if desired, another storm-strip arranged on the front side of the overlapping portion *a*; or, if desired, but one storm-strip may be employed 105 even when the coat has a storm-shield arranged inside or outside, but in case a single storm-strip is employed, it will be arranged, preferably, on the front side of the innermost overlapping portion.

Instead of forming the storm-strip by turning over the edge of one of the over-

lapping portions and thereby incidentally forming a binding at the edge, a binding *g* may be secured to the edge, see Fig. 5, which is folded thereon so that one edge is left 5 unattached and thereby permitted to extend forward.

A coat having three overlapping portions at the front opening, arranged as here shown, one portion being inserted between 10 the other two portions, the passage between said portions is tortuous by reason of turning abruptly at an angle at the point of attachment of the two overlapping portions between which the other overlapping portion 15 is inserted, and when the entrance to said passage gapes open between the fastenings, as it will do, either by the bulging outward of the outer overlapping portion or by the bulging inward of the inner overlapping 20 portion, the opening thus produced extends only to the bend. The water which is blown into this passage or which flows into the passage and collects on the walls of the passage, will be prevented from following along 25 the passage, around the bend, and finally reaching and wetting the wearer, by means of the storm-strip here shown, which is purposely located remote from the entrance to the passage, being at or near the bottom of 30 the opening which is formed by the entrance to the passage gaping open, or beyond such point.

I claim:

1. A storm-coat having a front opening

with three overlapping closing portions 35 therefor, arranged two at one side and one at the other side of said opening, whereby a tortuous passage is produced between said portions, and a storm-strip arranged on the front side of an inner overlapping portion 40 at a point remote from the entrance to said passage, whereby the water which flows into and is blown into said passage, when the entrance thereto gapes open, and which collects on the surfaces thereof, is checked and 45 is directed downward, substantially as described.

2. A storm-coat having three overlapping portions at the front, two of which are attached together remote from their edges, 50 and the other is adapted to be inserted between them, and a storm-strip arranged on the front side of the middle portion, remote from the entrance to the passage between said portion and the outer portion, and another storm-strip arranged on the front side of the inner portion remote from the entrance to the passage between said portion and the middle portion, substantially as described. 55

In testimony whereof, I have signed my name to this specification, in the presence of two subscribing witnesses.

WALTER S. BARKER.
